UNITED STATES PATENT OFFICE.

HERBERT L. STILLMAN, OF CHARLESTOWN, RHODE ISLAND.

RAIL FOR RAILWAYS.

SPECIFICATION forming part of Letters Patent No. 513,445, dated January 23, 1894.

Application filed October 31, 1892. Serial No. 450,439. (No model.)

To all whom it may concern:

Be it known that I, HERBERT L. STILLMAN, a citizen of the United States, residing in Charlestown, in the county of Washington and State of Rhode Island, have invented certain new and useful Improvements in Rails for Railways; and I do hereby declare that the following is a full, clear, and exact description thereof, reference being had to the accompanying drawing, and to the letters of reference marked thereon, which forms a part of this specification.

This invention has relation to a continuous compound rail adapted to all forms of railways; the same being an improvement on my United States patent of August 26, 1890.

The invention will be fully understood from the following description, when taken in connection with the accompanying drawing, 20 in which—

a a a, represent the left hand supporting rail sections.

b b b, represent the right hand supporting rail sections.

c c c, represent the central or tread portion of the rail.

d d d, represent cross-tie supports.

fff, represent joints in the sections.

In operation, after apertures have been 30 formed through the rail sections, I place the sections of the rail together so that two whole continuous sections shall be opposite every

broken joint, as seen in the drawings, in which the righthand supporting section joints over second tie, with central and left hand sections continuous. Over the fourth tie, the left hand supporting section joints with the right hand and central sections continuous. Over the third tie, the central or tread section of the rail, joints with both lateral supporting rail sections continuous. This process of double long laps against every single break, being continuous without limit, to any length of this compound rail desired, the sections in this position being firmly secured by 45 bolts or other fastenings. By this construction it will be seen that extra strong joints will be made by very long laps, and two whole, continuous sections appear against every single break.

Having described this invention, what I claim is—

The compound continuous rail herein described, consisting of a central or tread section with two lateral supporting sections, 55 with joints breaking so as to everywhere present two whole sections against every break, as applied and laid on cross ties, so that every joint break shall be supported by a cross tie, substantially as specified.

HERBERT L. STILLMAN.
